MULTI CONTACT ELECTRICAL CONNECTOR

John F. Maurer, Mechanicsburg, Pa., assignor to AMP
Incorporated, Harrisburg, Pa.

Filed Jan. 19, 1961, Ser. No. 63,629

Term of patent 14 years

(Cl. D26—1)

FIGURE 1 is a perspective view showing the top and front portion of the connector.

FIGURE 2 is a perspective view showing the underside and back of the connector.

The dominant features of my design reside in the projecting four corners with fluting thereon and the oval-shaped depressions as on top, front, and back of the connector all as shown.

I claim:

The ornamental design for a multi contact electrical connector, substantially as shown and described.
